ABSTRACT: A writing device with a tracing point comprises detachable head fitted with a writing member and ink conducting means so that when the head is mounted on the writing device ink is fed to said member enabling one to write with the same. The member is a nib or a ball.

WRITING DEVICE

FIELD OF THE INVENTION

The invention relates to writing devices comprising writing instrument having a tracing point.

PRIOR ART

Writing instruments having a nib, or fountain pens as well as writing instruments having a ball, or ballpoint pens, are known. Writing instruments, sometimes called markers, or tracers, the writing member of which is made up of a tracing point of fibrous or cellular material, are also known.

Up to now these instruments are distinct.

SUMMARY OF THE INVENTION

The present invention has as its object the provision of a writing instrument which may be used at will as a fountain pen or as a ballpoint pen or as a marker.

According to the invention, there is provided a writing device comprising a writing instrument having a tracing point, the writing device further comprising a detachable head having a writing member other than a tracing point and ink conduction means for controlled feeding of the said member when the head is mounted over the tracing point on the writing instrument.

The invention will be well understood from the description of embodiments thereof which follows, given by way of example.

BRIEF DESCRIPTION OF THE DRAWINGS

FIG. 1 is a sectional view of the front part of a marker;

FIG. 2 is a longitudinal sectional view of a nib head;

FIG. 3 is a longitudinal sectional view of a writing device according to the invention, when utilizable as a fountain pen;

FIG. 4 is a view similar to FIG. 3, but for another embodiment;

FIG. 5 is a sectional view, on a larger scale, of a part of the device shown in FIG. 4;

FIG. 6 is a longitudinal sectional view of the front part of another embodiment of a writing device;

FIG. 7 is a plan view, on a larger scale, of a conduit of the device of FIG. 6;

FIG. 8 is a rear end view of the conduit of FIG. 7;

FIG. 9 is a view similar to FIG. 7, but for another embodiment;

FIG. 10 is a sectional view along the line 10-10 in FIG. 9;

FIG. 11 is a view similar to FIGS. 3 and 6, but for a variant;

FIG. 12 is a sectional view, on a larger scale, of a part of the device shown in FIG. 11;

FIG. 13 is a view of the rear end of a writing device; and

FIG. 14 is a similar view to that of FIG. 13, with a writing head in position.

DESCRIPTION OF THE PREFERRED EMBODIMENTS

Reference is first made to FIGS. 1 to 3. The writing instrument comprises a marker A (FIG. 1), the body 10 of which is connected by tapping 11 and thread 12 to a point device 13. This point device comprises a body 14 and a rear tubular appendage 15 carrying thread 12. The point device 13 is bored axially along a passage 16 in which is housed a marking member 17 in the shape of a stem and terminating in a point 18, usually of a conical shape, having a tip 19. In the stem 17 a groove 20, communicating with the exterior by a port 21, ensures the entry of air. A striker 22 is driven into an internal bore 23 of the tubular appendage 15 of the point device. It has a central passage 24, which extends the passage 16 and which houses the rear part of the stem 17; at its rear end 25, the striker terminates in an oblique cutting edge 26. Housed inside the body 10 is a store of ink which is either of a free level—and which can be contained in a cartridge, then opened by cooperation with the striker 22—or else present in a capillary charge.

This marker can be used in the conventional manner.

With the marker A there cooperates a nib device B, which comprises a body 30 (FIG. 2), the rear edge 31 of which caps the edge 27 of a shoulder 28 on the point device 13 (FIG. 3), so that the lateral surface 32 of the body 30 is in extension of the surface 29 of the body 10. A ring 33 is fitted in a groove 34, of rectangular section, in the body 10. A rear bore 35 of the body 30 cooperates with the lateral surface 36, of conjugate shape, of the point device. A front bore 37 of the body 30 houses a nib 38, made of gold or steel, of tubular or other shape, the rear edge 39 of which abuts against a shoulder 40 in the body 30.

Arranged inside the nib 38, and lining a large portion of its internal surface 41, is a tongue 42 made from spongy material forming a fold 43 at its rear part in the region of the shoulder 40 from which it extends following an extension 44, of prismatic or conical shape, or prism-conical, as far as an edge 45 substantially in contact with the internal surface of the bore 37.

When the marker A is capped with the nib device B, as shown in FIG. 3, the tracing point 18 comes into contact with the extension 44 of the tongue 42, so that a capillary communication is established between the nib 38 and the ink store, through the medium of the tongue 42, the extension 44, and the stem 17, the instrument being able to function in the manner of a fountain pen.

If necessary, more especially when the ink store of the tracer is free level, compensation means are housed inside the nib 38 and/or the bore 37 to retain ink which escapes from the store, for example in the case of a temperature rise.

When one wishes to use the instrument as a marker once again, it is sufficient to remove the nib device B and the instrument resumes its configuration shown in FIG. 1. Equally, if, for any reason, the nib is damaged, the instrument can continue to be used for writing by returning it to its marker state.

Reference will now be made to FIG. 4, which is similar to FIG. 3, but shows another embodiment. In this embodiment, a tongue 50, with which the nib is in contact, has a descending branch 51 (FIG. 5), which is in contact, by its rear face 52, with a washer 53 made of more rigid capillary material, for example porous material, which has an orifice 54 in the shape of a truncated cone. The point 18 is housed in this orifice upon the positioning of the nib device B', thus ensuring a contact of large area between the washer 53 and the branch 51. In this embodiment, the compensation means 55 for retaining ink form part of the marker A and are operative both when the writing instrument is used as a marker and when it is used as a fountain pen.

Reference will now be made to FIGS. 6 to 8. The fountain pen head 60 is adapted to fit on the front end of a writing instrument 61, the writing member of which is made up of a stem 62 terminating in a point 63. The head 60 comprises a body 64 having a cylindrical bearing surface 65 cooperating with a shoulder 66 on the writing instrument 61 for detachable mounting. The head 60 houses a conduit 67, made up of a core 68 of plastic material of a generally cylindrical shape, having a beveled front face 69. The core 68 and the body 64 define an annular gap in which a nib 70 is housed.

The core 68 has a capillary bore 72 of circular transverse section which is blind at its front end 86 and open at the rear end 71 of the core to receive the point 63 when the head 60 is placed on the writing instrument 61.

A longitudinal and radial slot 73, the orifice 74 of which on the external surface 75 of the core 68 is situated in the middle of the nib 70, opens into the bore 72. The slot 73 has an in-curved front edge 76.

Other longitudinal slots 77 and 78 also open into the bore 72 and have orifices 79 and 80 which are arranged obliquely. The ends 81 and 82 of the slots on the front face 71 are spaced from the longitudinal median plane of the core 68 and the opposite ends have a common juncture with the slot 73. The distance between the parallel faces 83 and 84 delimiting a slot is smaller than the diameter of the bore 72, so that the capillary path thus offered to the ink as from the point 63 is of a

decreasing dimension as far as the nib 70, which is favorable to controlled feeding.

Reference will now be made to FIGS. 9 and 10. In this embodiment, the core 90 of the conduit not only has a central bore 91, blind at its front end and from which there emerges a radial slot 92, but also semicircular transverse grooves 93, four in number in the example shown, namely 93₁ ... 93₄, which contribute to the controlled feeding of the nib.

In the embodiment of FIGS. 11 and 12, the tracer 61, the constitution of which is similar to that which has been described previously, can be capped by a ball writing device 110 so constituted that the feed of the ball is ensured from the tracing point 63.

The ball writing device 110 comprises a tubular body 111 having a transverse vent 131 and an external surface 112 which, initially substantially cylindrical, tapers to an ogival or conical end 113. The internal surface of the body 111 comprises a bore 114 adapted to cooperate with the shoulder 66 of the writing instrument, a bore 115 of smaller diameter adapted to cooperate with the cylindrical part 103 of the writing instrument, a bore 116 of even smaller diameter, which houses the front end 104 of the writing instrument, and a bore 117. In this bore 117 a ball head 118 is tightly fitted. The ball head 118 comprises a tubular body 119 in which is mounted a ballpoint 120. The end 121 of the ball point 120 is crimped so as to maintain a ball 122 at the end of a passage 123. This passage is extended towards the rear by an enlarged part 124.

Housed inside the ball head 118, in its axial passage, is a stem 125, made from a synthetic sponge or similar material having a high coefficient of swelling, for example of the order of five, when it passes from the dry state to the wet state. The stem 125 is in contact, at its front face 126, with the ball 122. The length of the stem is such that, when it is inserted in the passage 123-124 and when its front face 126 is in contact with the ball 122, it protrudes from the rear face 127 of the ball head 118 sufficiently for it to be folded back at its end. When the stem is wet, the folded branch 128 comes into contact with the internal surface 129 of the barrel 119. When the stem is wet it is also in contact, at its lateral surface 130, with the bore 123 and its front face 126 corresponds closely to the spherical shape of the ball 122.

When the ball writing device 110 is placed on the front part of the tracer 61, as shown in FIG. 12, the tracing point 63 assumes contact with the curved part 123 which forms the external surface of the fold of the rear end of the stem as shown in dotted lines in FIG. 7. Then, when the device 110 comes into abutment at its annular face 133 against the shoulder 66, there is surface contact between the tip of the point 63 and the curved part 132, as shown in solid lines in FIG. 12, the friction developed upon the contact between the branch 128 and the bore 129 opposing a general displacement of the stem 125. The ink can then proceed by capillarity between the point 63 and the ball 122, where it effects the satisfactory feed of this latter for writing.

When one removes the ball device 110, by simple pulling,

the writing instrument can be immediately used as a tracer. If one then caps the tracer with the nib device 60, it can be used as a fountain pen.

In FIGS. 13 and 14, a writing instrument 100 having a tracing point as described above has, on its rear part, a cylindrical projection 101, which can comprise a metallic packing, on which the body of the fountain pen head or of the ball head can be fitted so that, when one wishes to use the writing device as a marker, and when thus its front part is free of the nib head 60, or of the ball head 110, this latter can be placed on the rear end of the instrument on the projection 101. The fountain pen head or the ball head thus placed on the rear end of the writing instrument can be protected by the usual cap.

I claim:

15. 1. A writing device comprising a writing instrument having a tracing point, ink reserve means connected to said point for capillary feed of ink thereto and a detachable head having a writing member and capillary ink conduction means adapted to cooperate with said point for the controlled feeding by capillarity of said writing member from said ink reserve means and via said point when said head is mounted over said tracing point.
20. 2. A writing device as claimed in claim 1, in which said writing member is a nib.
25. 3. A writing device as claimed in claim 2, wherein said conduction means comprises an ink feeding tongue in contact with said nib, said tongue including a leg with which the tracing point cooperates when the head is mounted over said tracing point.
30. 4. A writing device as claimed in claim 2, wherein the nib is lined by an ink feeding tongue which is extended by a transverse leg covering a washer of porous material, said washer having a central orifice which is of a shape corresponding with that of the tracing point.
35. 5. A writing device as claimed in claim 1, wherein said ink conduction means comprises a core having a bore adapted to cooperate with said tracing point, and further comprising a nib supported by said core and having slots establishing an ink communication between said bore and the zone of the surface of the conduit with which the nib is in contact.
40. 6. A writing device as claimed in claim 5, wherein said slots comprise a radial longitudinal slot and oblique slots.
45. 7. A writing device as claimed in claim 5, wherein the core has a middle longitudinal slot and transverse grooves.
50. 8. A writing device as claimed in claim 1, wherein said writing member is a ball.
55. 9. A writing device as claimed in claim 8, wherein said head comprises a stem of spongy material having a high coefficient of swelling in contact with the ball at its front end and the rear end of which is folded and in contact with said point when said head is mounted on said point.
60. 10. A writing device as claimed in claim 1, wherein said writing instrument comprises a body and means at the rear part of said body to receive the detachable head.
